WATER TOY FIGURE

Leon R. Cohen, Springfield, Mass.

Application February 20, 1950, Serial No. 8,032

Term of patent 7 years

(Cl. D34—15)

To all whom it may concern:

Be it known that I, Leon R. Cohen, a citizen of the United States, residing at Springfield, in the county of Hampden and Commonwealth of Massachusetts, have invented a new, original, and ornamental Design for a Water Toy Figure, of which the following is a specification, reference being had to the accompanying drawings forming part hereof.

Fig. 1 is a front perspective view of a water toy figure, showing my new design;

Fig. 2 is a rear perspective view thereof; and

Fig. 3 is a side perspective view of the water toy figure shown in Figs. 1 and 2.

The essential features of my design are shown in full lines.

I claim:

The ornamental design for a water toy figure, as shown and described.

LEON R. COHEN.
